UNITED STATES PATENT OFFICE

CHARLES KUCHAUSKAS, OF WATERBURY, CONNECTICUT

SPRING DOOR CLOSER

Application filed August 29, 1929. Serial No. 389,191.

This invention relates to spring door closers and is directed more particularly to a device of this character which is intended primarily for returning a double swinging door or gate to normal or closed position.

The primary object of the present invention is to provide a spring door closer which shall be particularly simple in construction and inexpensive to manufacture and which shall be easy to install.

Another object is to provide a device of this character which shall be readily adaptable to various types of installations and which shall be equally effective in each instance.

With these and other objects in view the invention may be stated to consist in the various novel features of construction and arrangement or combination, all of which will be fully described hereinafter and pointed out in the appended claims.

In the drawing accompanying and forming part of this application, Fig. 1 is a fragmentary elevation of a fence and gate fitted with a device constructed in accordance with my invention;

Fig. 2 is an enlarged fragmentary top plan view thereof;

Fig. 3 is sectional view taken on the line 3—3 of Fig. 2;

Fig. 4 is a fragmentary side elevation of a fence and gate fitted with a modified form of my invention; and

Fig. 5 is a sectional view taken on the line 5—5 of Fig. 4.

Referring particularly to Figs. 1-3 inclusive, a spring door closer constructed in accordance with my invention comprises a pair of base plates 10, 10 which are interconnected by a coil spring 11. Each base plate is formed

with suitable apertures to receive screws 12 or other fastening means for mounting the device. The adjacent or inner end of each base plate is formed with a pair of upstanding ears 13, 13 which may be conveniently formed by bending the metal of the base plate at right angles.

Suitable lugs 14 are provided on the ears by slitting the metal and bending it in circular shape about a convolution of the spring. A similar lug 15 is also formed be-

tween the ears 13 and these lugs serve to secure the spring to the base plates.

In use, the gate 16 or other closure member is mounted on suitable double swinging hinges 17. The spring hinge is mounted between the gate and its support 18, as for example on the top thereof as shown in Figs. 1 and 2. The spring 11 will flex as the gate swings in either direction and always return it to normal or closed position.

In Figs. 4 and 5 I have shown a slightly modified form of my invention which is adapted for mounting where the surface of the gate and the surface of the support therefor are not disposed in the same plane. In this form the base plate 10^a and coil spring 11^a are identical with those described above. Secured to the opposite end of coil spring 11^a is a bracket 20 which is preferably formed of sheet metal and provided with depressions 21 to receive a convolution of the spring 11^a. Suitable apertures are formed in the bracket for the reception of screws 22 or other suitable fastening means. In this form of my invention it will be noted that the base plate 10^a and bracket 20 are arranged for mounting on surfaces disposed at right angles to each other. The operation of this form of device is identical with that previously described.

While there has been disclosed in this specification one form in which the invention may be embodied it is to be understood that this form is shown for the purpose of illustration only and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. A device of the character described comprising a pair of base members arranged in spaced relation and interconnected by a horizontal coil spring, a portion of the metal of each of said base members being bent about a convolution of said spring to secure them together.

2. A device of the character described comprising a pair of base members arranged in spaced relation, each of said base members having an upstanding portion provided with lugs, and a coil spring interconnecting said base members and having the end convolutions engaged in said lugs, said base members being adapted to be attached to a hinged member and a supporting frame at oppositely alined positions.
- 10 In testimony whereof, I have affixed my signature to this specification.

CHARLES KUCHAUSKAS.
